UNITED STATES PATENT OFFICE

139,593

DESIGN FOR A DOLL

Althea J. Bressler, Glassboro, N. J., assignor of one-half to Charles B. Kain

Application July 31, 1944, Serial No. 114,654

Term of patent 14 years

(Cl. D34—4)

To all whom it may concern:

Be it known that I, Althea J. Bressler, a citizen of the United States, residing at Glassboro, in the county of Gloucester and State of New Jersey, have invented a certain new, original, and ornamental Design for a Doll, of which the following is a specification, reference being had to the accompanying drawing, forming part thereof.

Fig. 1 is a front view of a doll embodying my invention.

Fig. 2 is a rear view of the doll shown in Fig. 1.

I claim:

The ornamental design for a doll, substantially as shown.

ALTHEA J. BRESSLER.
